UNITED STATES PATENT OFFICE.

FREDERICK W. GLASS, OF NEWBURGH, NEW YORK.

DEVICE FOR TILTING THE MATTRESS-SUPPORTING FRAME OF BEDSTEADS.

Application filed June 15, 1922. Serial No. 568,414.

To all whom it may concern:

Be it known that I, FREDERICK W. GLASS, a citizen of the United States, residing at Newburgh, county of Orange, State of New York, have invented certain new and useful Improvements in Devices for Tilting the Mattress-Supporting Frame of Bedsteads, of which the following is a specification.

This invention relates to a novel device for tilting or raising the mattress supporting frame of bedsteads and the parts supported thereon, such as the mattress and bedclothes, in order to permit a person to sweep or clean the floor beneath the bed without moving the bedstead.

The general object of the invention is to provide a relatively simple and inexpensive device of this character which may be conveniently and quickly attached to most of the standard makes of bedsteads now in use.

To these ends the invention further consists in the novel details of construction and combination of parts more fully hereinafter described and particularly pointed out in the claims.

Referring to the drawings forming a part of this specification, in which like numerals designate like parts, in all the views:

Figure 1 is a cross sectional view of a bedstead showing the invention applied thereto.

Figure 2 is an enlarged cross sectional view taken on the line 2—2 of Figure 1 with the supporting bracket shown in full lines.

Figure 3 is an enlarged cross sectional view taken on the line 3—3 of Figure 2.

Figure 4 is a perspective view of the casing or drum.

Figure 5 is a perspective view of one form of end extension piece and

Figure 6 is a perspective view of another or modified form of end extension piece.

Referring to the drawings in detail, 1 designates the frame of the bedstead, 2 the mattress supporting frame mounted thereon and 3 the device for tilting or raising the mattress frame to the position shown in dotted lines in Figure 1. Both the bedstead and mattress supporting frame may be of any usual or preferred construction and constitute in themselves no portion of the present invention.

The device for raising and holding in a tilted position the mattress frame and parts

supported thereon comprises a pair of casings or drums 4 (only one of which is shown) from which project inwardly a pair of brackets 5 for connecting the device to the mattress supporting frame. These brackets have their outer ends provided with bearings 6 for receiving the longitudinal side bar 7 of the mattress supporting frame, as shown in Figures 1 and 2, and by providing the brackets with a removable cap 8 the device may be quickly and conveniently connected to the bar 7. Both of the casings 4 are closed by the end pieces 9 and 10, the end 10 being provided with an extended horizontal bearing portion 11 which fits within a bearing 12, provided in the extension pieces 13 which are secured to the head and foot sections of the bedstead at one side thereof. The extension pieces form a means for conveniently connecting the device to a bedstead of the usual or standard construction as they are provided with the usual tapering T-shaped headed projections 14 for engaging the sockets 15 (only one of which is shown, see Figure 2) provided on each side of the head and foot section of the bedstead. A coil spring 16 is mounted within each of the drums or casings and these springs are employed to assist in raising the mattress supporting frame and the load carried thereby and also to assist in holding the frame and the load carried thereby in its upper or tilted position as shown by dotted lines in Figure 1. Each of the springs has one of its ends secured within the end piece 9, and the other of its ends project through the end piece 10 and bearing portion 11 and is bent downwardly at right angles to the bearing portion and secured in an opening 17 provided in the extension piece 13 as shown in Figure 3. To provide for passing the end of the spring through the end piece 10 and bearing portion 11, both the end piece and bearing portion are split as shown in Figure 4. Set screws 18 and 19, passing through the casings and engaging the end pieces 9 and 10 are provided for securing the end pieces in position on the casings. The end piece 9 is provided with a squared projection 20 so that a wrench or other implement may be used for turning the end piece within the casing to regulate the tension of the spring when occasion requires so that the proper counter balancing effect may be obtained. This construction and arrangement renders

it possible to vary the tension of the springs, as desired, it being obvious that by first loosening the set screws 19 and turning the end pieces 10 one way the tension on the 5 springs will be increased and by turning the end pieces the other way the tension will be decreased. After the desired adjustment has been made the set screws 19 are then tightened.

10 In order to prevent the mattress from slipping off of its supporting frame when raised to its upper position, supporting brackets 22 are provided on the casings 4. These brackets may be secured to the casings in any suitable manner such as by being riveted thereto as shown.

When the mattress supporting frame 2 and parts carried thereby are in their lowermost or normal position, the frame 2 is 20 adapted to engage and be supported by the side bar 24 of the bedstead. When in this position the springs are under tension and exert a force tending to swing the mattress frame upwardly. Now when the outer or 25 front side of the mattress frame is lifted or swung upwardly the springs act or co-operate with the lifting movement and thus greatly assist the operator in tilting the mattress frame to its upper position. The 30 frame is swung downwardly with exertion of sufficient manual power to overcome the force of the springs until the mattress frame reaches its horizontal position, whereupon the frame, due to its weight, overcomes the 35 force of the springs and remains in its lower position.

To prevent the accidental tilting of the mattress supporting frame and parts carried thereby, a safety latch 25 is provided. This 40 latch is pivotally connected as at 26 to one side of the mattress frame and is suspended therefrom so that when the mattress frame reaches its horizontal position the hooked portion of latch will engage the side 45 bar 24 of the bedstead, as shown in Figure 1. When it is desired to swing the mattress supporting frame upwardly the operator throws the latch out of engagement with the side bar of the bedstead.

50 To prevent the mattress frame and parts supported thereon from being tilted beyond its upper or vertical position the drums or casings are provided with lugs or lateral extension pieces 28 which are arranged to 55 engage the projections 29 extending from the outer sides of the extension pieces 13 when the mattress frame is tilted to its upper position.

In the modification shown in Figure 5 60 the extension piece 13 is shown provided with an arrow shaped headed extension 30 for engagement with a similar shaped socket with which some makes of bedsteads are provided.

65 It is obvious that those skilled in the art

may vary the details of construction and arrangement of parts without departing from the spirit of my invention, and, therefore, I do not wish to be limited to such features, except as may be required by the 70 claims.

What I claim is—

1. A device for tilting the mattress supporting frame of bedsteads comprising a drum pivotally and detachably connected 75 to the bedstead, brackets carried by said drum for detachably securing the mattress frame thereto, a coil spring mounted within the drum and having one end secured to the drum and its other end passing through the drum and secured to the frame of the bedstead and set screws mounted on the drum for regulating the tension of the spring.

2. A device for tilting the mattress supporting frame of bedsteads comprising extension pieces having T-shaped headed projections detachably connected to the frame of the bedstead at one side thereof, drums pivotally and detachably connected to the extension pieces, and coil springs mounted 80 within the drums and having one end secured to the drum and the other ends passing through the drum and secured within the extension pieces.

3. A device for tilting the mattress supporting frame of bedsteads comprising extension pieces, detachably connected to the frame of the bedstead at one side thereof, drums pivotally connected to the extension pieces, coil springs mounted within the 90 drums and having one end secured to the drum and the other ends passing through the drum and secured within the extension pieces, and means mounted on the drums 100 and engaging the extension pieces for limiting the movement of the mattress supporting frame in one direction.

4. A device for tilting the mattress supporting frame of bedsteads comprising extension pieces detachably connected to the frame of the bedstead at one side thereof, drums pivotally connected to the extension pieces, coil springs mounted within the 110 drums and having one end secured to the drum and the other ends passing through the drum and secured within the extension pieces, means mounted on the drums for regulating the tension of the springs and means mounted on the drums and engaging the extension pieces for limiting the movement of the mattress supporting frame in one direction.

In testimony whereof, I have signed my name to this specification in the presence of 125 two subscribing witnesses, this 3rd day of June 1922.

FREDERICK W. GLASS.
